UNITED STATES PATENT OFFICE

92,354

DESIGN FOR A GASOLINE PUMP

James E. Jones, Anderson, Ind.

Application March 15, 1934, Serial No. 51,052

Term of patent 14 years

To all whom it may concern:

Be it known that I, JAMES E. JONES, a citizen of the United States of America, residing at Anderson, in the county of Madison, and State of Indiana, have invented a new, original, and ornamental Design for Gasoline Pumps, of which the following is a specification, reference being had to the accompanying drawing, forming part thereof.

In the drawing:—

Figure 1 is a front elevation of the gasoline pump; and

Figure 2 is a side elevation thereof.

I claim:—

The ornamental design for a gasoline pump, as shown.

JAMES E. JONES.
